UNITED STATES PATENT OFFICE.

ALEXANDRE GUELLE, OF PARIS, FRANCE, ASSIGNOR TO CHENEY
BROTHERS, A CORPORATION OF CONNECTICUT.

DESIGN FOR TEXTILE FABRIC.

No. 37,702.

Specification for Design.

Patented Nov. 28, 1905.

Application filed October 5, 1905. Serial No. 281,534. Term of patent 3½ years.

To all whom it may concern:

Be it known that I, ALEXANDRE GUELLE, a citizen of the French Republic, residing at the city of Paris, in the Republic of France, have invented a new, original, and ornamental Design for Textile Fabrics, of which the following is a specification, reference being had to the accompanying drawing, forming a part thereof.

The figure is a plan view of the fabric, showing my new design.

I claim—
The ornamental design for a textile fabric, as shown.

ALEXANDRE GUELLE.
